NOSE PAD ARM CONSTRUCTION

Louis Vitolo, Brooklyn, N. Y., assignor to Century
Oxford Manufacturing Corp., Brooklyn, N. Y.

Application December 26, 1940, Serial No. 371,617

1 Claim. (Cl. 88—49)

My invention relates to nose pad construction for eye-glasses and has reference more particularly to the coupling of the pad proper with the supporting arm therefor.

The object of the invention is to provide a simple and inexpensive mounting that requires no special tools for coupling the pad to the supporting arm.

Another object of the invention is to provide a pad mounting which will have proper play or 10 rocking movement on the arm without danger of separation between the pad and the supporting arm for same.

With this and other objects in view, the invention consists of certain novel features of construction which will be particularly pointed out in the appended claim.

In the accompanying drawing,

Figure 1 is a vertical section through a nose pad mounting embodying my invention.

Figure 2 is a section on line 2—2, Figure 1 and

Figure 3 is the elevation of the end of the supporting arm for the pad before it is connected to the pad.

Referring to the drawing, 5 is a metallic plate which is imbedded into the plastic material 6 shaped to form the pad, and a lug 7 forming an integral part of the plate 5, projects through the plastic material on the rear face of the pad.

The lug 7 has an aperture 8, running transversely of the longitudinal axis of the pad and substantially parallel to the faces thereof.

A supporting arm 9 has its free end 10 enlarged, and in the enlarged part, an orifice 11 of 35 substantially rectangular shape is formed to receive therethrough the lug 7 of the pad.

The orifice 11 of the arm 9 has trunnions 12 disposed on the longer sides of the orifice 11. These trunnions 12 are adapted to enter the 40 aperture 8 in the lug 7 from the opposite end of said aperture 8 when outer sides 13 of the enlarged portion 10 of the arm 9 are squeezed while the lug 7 is located in said orifice 11.

It would therefore be apparent that the dis-

tance between the trunnions 12 in the orifice 11 are sufficiently apart to permit the lug 7 to pass into the orifice 11, in consequence when the enlarged part 10 of the arm 9 is squeezed, as previously stated, the trunnions serve as pivots for the pad on the arm 9, in addition, preventing the pad from being separated from the supporting arm while permitting the pad to oscillate on the trunnions as an axis.

It is evident that in the manufacture of the arm 9 the orifice 11 formed in the enlarged part 10 of the arm has the distance between the trunnions 12 sufficiently apart to permit the lug 7 of the pad to pass through the orifice 11. The relation between the lug 7 of the pad and the supporting arm engaging it is such that the trunnions 12 and the aperture 8 are in a substantial alignment, and the mere pressing of the sides 13 of the enlarged portion 10 of the arm 9 brings the trunnions 12 into the aperture 8.

The material used for the arm 9 is sufficiently pliable to perform the operation described and to permit the adjustment of said arm with the pad for different types of eye-glass mountings.

The orifice 11, with the trunnions 12 therein, presents in its peripheral outline the outline of the capital letter H disposed transversely of the arm's length.

I claim:

30 A nose pad unit comprising, a pad having an apertured lug on the rear face thereof, a supporting arm terminating with an orifice in the shape outlining the capital letter H, which is disposed transversely of the arm length, said orifice being adapted to receive the lug, the portion of the orifice outlining the transverse part of the letter constituting trunnions adapted to align with the aperture of the lug when the same is inserted into the orifice, said trunnions being adapted to enter the aperture of the lug when the sides of the said letter are forced toward each other, whereby said lug is mounted to rock on said trunnions in said arm.

LOUIS VITOLO.
